(57) **CLAIM**

The ornamental design for an air cleaner cover, as shown and described.

DESCRIPTION

FIG. 1 is a front perspective view of an air cleaner cover of the present invention.

FIG. 2 is a front view of the air cleaner cover of FIG. 1.

FIG. 3 is a rear view of the air cleaner cover of FIG. 1.

FIG. 4 is a top view of the air cleaner cover of FIG. 1.

FIG. 5 is a bottom view of the air cleaner cover of FIG. 1.

FIG. 6 is a left side view of the air cleaner cover of FIG. 1; and,

FIG. 7 is a right side view of the air cleaner cover of FIG. 1.

The broken line showing of the environment is for illustrative purposes only and forms no part of the claimed design. The broken lines which define portions of the air cleaner cover of the claimed design form no part thereof.

1 Claim, 5 Drawing Sheets
